UNITED STATES PATENT OFFICE

147,948

DESIGN FOR A DOLL

Myer Abel, Hamilton County, Ohio

Application June 14, 1946, Serial No. 130,726

Term of patent 3½ years

(Cl. D34—4)

To all whom it may concern:

Be it known that I, Myer Abel, a citizen of the United States, residing in the county of Hamilton and State of Ohio, have invented a new, original, and ornamental Design for a Doll, of which the following is a specification, reference being had to the accompanying drawing, forming a part thereof.

Fig. 4 is a perspective view of the doll's head. The dominant feature of the design resides in the head portion shown in full lines.

I claim:

The ornamental design for a doll, substantially as shown and described.

MYER ABEL.
